AIR CIRCULATOR

Joseph H. Woodward, Miami, Fla.

Application May 18, 1950, Serial No. 162,690

7 Claims. (Cl. 230—259)

1
My invention relates to improvements in methods and means of inducing air circulation utilizing centrifugal force as the impelling medium and has as its principal object the provision of a centrifugal air circulating rotor, semi-spherical in contour to intake air through a center opening or openings and to forcibly expel this air over a radius of 360 degrees on the periphery to the free atmosphere surrounding it; thus creating a field of moving air extending to an appreciable distance throughout the surrounding space.

Another object of my invention is to provide an air circulating unit as a whole, of the character above described and to contain the motor or driving member wholly or partially within the confines of the air circulating unit, thus providing for the additional valuable feature of compactness.

Another object of my invention is to provide an air circulating rotor of the character described and embodying within its construction an inner shell that conceals the motor from view, adding to the appearance, and renders the operation more quiet and efficient. It also contributes to the features of strength and stability.

In practical application it is necessary that the motor thus inserted wholly or partially into the confines of the air circulating unit as a whole, be provided with a method or means of reducing the operational temperature of the motor, to avoid overheating.

Another object of my invention is to provide an air circulating rotor of the character described and additionally equipped with auxiliary air impelling blades to cause air to circulate specifically for the purpose of cooling the motor, or driving member.

Another object of my invention is to provide an air circulating unit of the character described and additionally equipped with a motor mount and base embracing openings to permit of the passage of circulated air specifically for the purpose of cooling the motor, or driving member.

Another object of my invention is to provide an air circulating unit of the character described that is above the average in efficiency in operation and performance.

Another object of my invention is to provide an air circulating unit of the character described that will operate without objectionable noise.

Another object of my invention is the provision of an air circulating unit of the character described, that embraces the essential feature of safety from physical injury to a greater degree than the majority of fans or air circulators now on the market.

2
Another object of my invention is to provide an air circulating unit of the character described adaptable to economical mass production methods through the use of plastic molding processes in manufacture.

Another object of my invention is the provision of an air circulating rotor of the character described of excessive rigidity, strength and stability by reason of its unique construction, consisting of an inner shell and an outer shell jointly reinforced by the air impelling blades interposed between them. Further strength and stability is provided for the inner shell, the outer shell and the blades at the axis by means of a reinforcing collar, and their embodiment in or attachment to a hub.

In manufacture it is necessary that this device, the air circulating rotor, be molded in at least two separate parts and later assembled. However when constructed of plastic, a plastic solvent can be used at all points or lines of attachment. The effect of this solvent is to dissolve the plastic material at the points and along the lines of attachment, which later hardens and in effect makes the air circulating rotor one complete embodiment of material.

Another object of my invention is the provision of an air circulating rotor of the character described that lends itself readily in process of manufacture to finally constituting one complete embodiment of material. This feature is very desirable from the standpoint of structural strength and stability.

Another object of my invention is to provide an air circulating unit of the character described embodying within its design, and its adaptability to the use of plastic materials a device of attractive contours with a wide selection of permanent colors.

Another object of my invention is to provide a compact air circulating unit, by reason of the motor being wholly or partially introduced into and encompassed by the air circulating rotor, to render it adaptable to use under tables, desks or in conjunction with other items of furniture.

Another object of my invention is to provide a centrifugal air circulating unit that creates a field of gently moving air throughout its sphere of influence as contrasted to the more violent concentrated movement of the beam of air set in motion by the propeller type of fans.

Other objects and advantages of my invention will become apparent from a study of the specifications read in connection with the accompanying drawings, wherein:

Figure 1 is a top plan view of an air circulating

3

unit constructed in accordance with my invention, with a portion of the rotor broken away;

Figure 2 is a sectional view on the line 2-2 of Figure 1;

Figure 3 is a detail sectional view on line 3-3 of Figure 1;

Figure 4 is a sectional view similar to Figure 2 with the inner shell of the air circulating rotor, the motor and motor base omitted;

Figure 5 is a plan view of the rotor with the outer shell broken away and showing a modification of the inner shell of said rotor; and

Figure 6 is a sectional view on the line 6-6 of Figure 5.

Referring to the drawings I have illustrated the air circulating rotor 1 of my invention as comprising an outer housing or shell 2 provided with annular air intake openings 3 and embodying a reinforcing collar 4. An inner housing or shell 5 embodies a hub 6. Main radial air impelling blades 7 are interposed between outer shell 2 and inner shell 5. Auxiliary radial air impelling blades 8 are illustrated as attached to inner shell 5. Hub 6 is used for attachment of air circulating rotor 1 to motor shaft 9.

Rotation of this air circulating rotor 1 is accompanied by the following results:

Air within the confines of the recesses of the air circulating rotor 1 is set in circular motion by the main radial air impelling blades 7 and also by the auxiliary radial air impelling blades 8. Centrifugal force acting in conjunction with the semispherical contour of outer shell 2 and inner shell 5 causes the air thus set in motion to seek release from the confines of the rotor 1 throughout 360 degrees on the extreme peripheries of outer shell 2 and inner shell 5.

Annular air intake openings 3 provide for the continuous replacement of air thus exhausted from the confines between outer shell 2 and inner shell 5. (Path and direction of air travel indicated by arrows.)

The motor base 14 is provided with slotted openings 16, a circular opening 15, and air passages provided in the spaces between the four motor mounts 11 and the clearance between the outside diameter of the motor 10 and the inside diameter of the collar 12, to provide for the continuous replacement of air exhausted by the auxiliary blades 8 from the confines of inner shell 5. (Path and direction of air travel indicated by arrows.)

It will be noted from the preceding that there are two distinct air circulating systems embodied in this air circulating rotor 1. I. e.: A main system actuated by the main radial air impelling blades 7 which is utilized for extending the movement of air to surrounding space, and an auxiliary system of air circulation utilized principally to circulate air to prevent overheating of driving unit or motor 10.

The foregoing detailed descriptions embrace several distinct and valuable improvements in methods and means, further advantages are outlined as follows:

Annular air intake openings 3 are a preferred form of this invention, in place of a large single opening. They provide (a) a guard against physical injury and (b) tend to reduce noise of operation. Explanation: A single air intake opening of equal area exposes a continuous length of the edges of main air impellers 7 to the incoming air stream. This results in considerably more air turbulence and operational noise than is the case when the incoming air is admitted through the spaced annular openings as illustrated.

Another distinct, valuable and original improvement in methods and means is embodied in the construction of the rotor 1. It will be noted that the relative contours of shell 2 and shell 5 are such as to narrow down the air passage as the exhaust air approaches the outlet indicated at 17. This slightly choking effect is of advantage in reducing operational noise, by retarding the flow of exhaust air at the point of discharge, a slight back pressure is created which forms an air cushion, so to speak at points of intake, and reduces air turbulence.

This slightly choking effect is also of advantage in tending to retard the flow of exhaust air to the effect that the air is retained between the confines of shell 2 and outer shell 5 until the air has accumulated more centrifugal kinetic energy, resulting in greater air velocity upon release, which in turn results in an extension of the radius of effective air movement in the surrounding space.

Another valuable result of this method and means of air circulation is in the air pattern that is established after operation for a period of time. Example: More or less centrally located in an enclosed space, room or compartment, this device gradually establishes a cycloid air pattern throughout the area.

Another original and valuable contribution to methods and means of air circulation embraced in this invention is the provision of radial edges Fig. 3 blades 7 being provided with radial edges Fig. 3 further minimize operational noise due to air turbulence at intake openings.

Another original and valuable contribution to method and means of circulating air embraced in this invention is a preferred positioning of radial edges of main air impelling blades 7 as illustrated in Fig. 4 and Fig. 5, wherein the radial edge of the blades 7 is illustrated as protruding partially into the intake openings 3. This preferred construction is utilized mainly to adapt the construction to molding processes, but also adds to stability of outer shell 2 as a whole.

Earlier models of this air circulating rotor consisted of but one shell, the air impelling blades, and a hub. Considerable air turbulence, hence operational noise, was developed along the inner edges of the blades, regardless of many contours that were experimented with.

Other original and valuable improvements in method and means of air circulation embraced in the construction of this air circulating rotor 1 is the provision of an inner shell 5. This form of construction lessens air turbulence and noise. It further increases mechanical stability. It adds to the appearance by concealing the motor from view.

Another original and valuable improvement in method and means embodied in this invention is the provision of the collar 4 as a reinforcement at the axis of outer shell 2.

Another original and valuable improvement in method and means embodied in this invention is the provision of a hub 6 embodied in the axis of the inner shell 5 and extending as illustrated through the orifice of the collar 4 embodied in outer shell 2. This form of construction was particularly designed to adapt the rotor to the processes of plastic molding, and achieve a maximum of strength. (Conceivably any thickness of material could be molded on the axis of either shell. Practically it is advantageous to gain any

thickness of material desired for strength at this point by embodiment of half the desired wall thickness on the axis in each respective shell.)

Another original and valuable improvement in methods and means of air circulation, and a necessary adjunct to render the operation of this device practicable, is embraced by the auxiliary air cooling system for the motor 10, consisting of: Auxiliary air impelling blades 8, the clearance or space between motor mount collar 12 and 10 motor 10, the spaces between the four sectional motor mounts 11 and motor base openings 15 and 16.

Another original and valuable feature of this invention is the provision of base collar 12 which adds stability to motor base 14; dampens transmission of motor vibration and noise to the surface of motor base 14 and further adds to attractiveness of appearance by concealing motor 10 from view.

Another original and valuable improvement in methods and means of air circulation is embodied in this device by the principles utilized to control the pattern, direction and width of the intake and exhaust air streams. Any desired fixed pattern may be obtained by the relative area embraced by the inlet openings as compared to the area embraced by the outlet openings (or opening). Example: The larger the intake opening as compared to the exhaust opening, the more 30 the beam of the exhaust opening will tend to bend toward the intake. Altering the area embraced in either the intake or outlet openings can be used to control the air pattern of the beam as desired. One simple method is to raise or 35 lower, or alter the position of the air circulating rotor 1 on the motor shaft 9 which can be provided for by a set screw 20 or other mechanical means, thus increasing or decreasing dimensions of exhaust opening between periphery of air circulating rotor 1 and surface of motor base 14, or an adjustable damper may be provided for over the intake openings. (This is illustrated in my patent application No. 123,222 series of 1948 claim No. 4.)

An alternative method and means of inducing air circulation, dispensing with the auxiliary air impelling blades, specifically for the purpose of prevention of operational overheating of the motor is illustrated in Figure 6. An annular opening 50 18 is provided in inner shell 5, thus providing for a partial replacement of exhausted air in the confines of the air circulating rotor to be obtained by means of this said annular opening and consequently causing a circulation of air through 55 the air passages provided in the motor mountings and motor base encompassing the motor.

While I have shown and described preferred embodiments of my invention, and preferred materials for manufacture, I do not desire to be limited to any of the details of construction shown and described herein, or the use of any specific materials, except as defined in the appended claims.

I claim:

1. A centrifugal air circulating unit that comprises a base, a motor mounted on said base with its output shaft projecting normally therefrom, a first shell, a second shell, a plurality of blades connecting said shells in spaced relation with said second shell disposed within said first shell, a hub contrally joined to said shells, said hub being detachably fixed to said motor shaft for rotation therewith, said first shell defining a plurality of openings in the vicinity of said hub to permit air to pass into the space between said shells, said shells having edges terminating adjacent said base and cooperating therewith to define an outlet for air, and means on said hub cooperating with said output shaft for varying said outlet to control the pattern of air discharged by said unit, said shells substantially enclosing said motor thereby rendering said unit compact.

2. A centrifugal air circulating unit as defined in claim 1 wherein a plurality of blades are joined to the inner surface of said second shell adjacent said motor to cause a circulation of air around said motor for the purpose of cooling said motor during operation of said unit.

3. A centrifugal air circulating unit as defined in claim 2 wherein said base defines an opening therein beneath said motor to permit air to pass within said second shell and be circulated by the blades joined to the inner surface of said second shell.

4. A centrifugal air circulating unit as defined in claim 3 wherein a collar is mounted on said base surrounding said motor for cooperation with said shells to direct air around said motor.

5. A centrifugal air circulating unit as defined in claim 1 wherein said plurality of blades project into said openings in said first shell.

6. A centrifugal air circulating unit as defined in claim 1 wherein the space adjacent the edges of said shells is restricted to produce a choking effect and create a back pressure in the space between said shells.

7. A centrifugal air circulating unit as defined in claim 1 wherein said second shell defines there-in an opening functioning as an inlet to the space between said shells and resulting in a circulation of air around said motor during operation of said unit.

JOSEPH H. WOODWARD.
